UNITED STATES PATENT OFFICE

JOHANN TUREK, OF STEINBACH, GERMANY, ASSIGNOR TO THE FIRM MALSCH & AMBRONN, OF STEINBACH, GERMANY, A FIRM COMPOSED OF WILLY MALSCH AND KARL AMBRONN

RECEPTACLE FOR FLOOR POLISHING SUBSTANCES AND THE LIKE

Application filed June 29, 1931, Serial No. 547,713, and in Germany November 26, 1930.

My invention relates to receptacles especially tins for liquid or semi-liquid floor-polishing substances of waxy or oily nature, and more particularly to a tin, for use in working connection with a stick or handle provided with a mop or brush as usually employed for floor polishing purposes.

According to the present invention there is provided in the tin an improved means for allowing a small portion of the liquid polishing wax or the like contained therein, to be automatically discharged from the receptacle when required or desired.

I am aware of the fact that it is known to firmly attach a tin to a mop stick or the like for the purpose of permitting the polishing substance to flow out during the polishing operation in order to be rubbed down or distributed over the floor by means of the brush or mop. To this end the receptacle or tin is usually provided with a small opening which is permanently kept open during the waxing operation so that the polishing substance can flow out continuously irrespective of the actual want. In some cases the discharging aperture is controllable and a means for manually opening and closing the same at intervals is provided for such control.

It has also been suggested heretofore to utilize the working pressure manually exerted on the stick of the mop, for controlling the discharge of the polishing substance from the receptacle. It will be seen, however, that in such a case the quantity of polishing material discharged at a time will not be adequate or correspond to the want, but will vary and depend upon the manual pressure required and applied at times for the rubbing and distributing purpose. Consequently parts of the floor will receive and be coated with polishing material in excess of what is necessary while others will be deficient in the said material of waxy substance.

The chief object of the present invention is to remedy the defects of the receptacles hitherto used in supporting connection with a mop stick, and with this object in view I so construct the receptacle or tin as to ensure momentary discharges of polishing sub-

stance to be delivered automatically therefrom independently of the working pressure manually imparted to the stick or the like and without requiring any particular manual operation for the purpose. This is due, 55 on the one hand, to the particular construction of the receptacle, especially the discharging means thereof, and on the other hand, to the observation or fact that the successive raising and lowering of the polishing 60 implement during the polishing operation can be utilized for causing small portions of the polishing substance to be automatically discharged from the receptacle at will, provided that suitable means are provided in 65 connection with the latter for the purpose in view.

The amount of polishing liquid to be discharged at a time may be very small depending upon the construction and adjustment of 70 the means provided for the discharging purpose, but by simply repeating the usual manipulation of raising the mop from the floor and subsequently dropping the same onto the floor with a certain vehemence and shock, the 75 quantity of polishing liquid to be discharged to the floor can be increased at will to any desirable amount, just as required by the condition of the floor.

A receptacle or tin constructed in accordance with the present invention and adapted for use in connection with the handle or stick of a mop or the like comprises a spring controlled valve and a valve seat or opening provided preferably in the bottom of the receptacle or tin. If required or preferred, even a plurality of valves, springs and valve seats or openings may be provided in or near the bottom of the tin or at any other suitable place of the walls of the latter.

According to the present invention the discharging valve is mounted in the tin in a manner that on sudden lifting the mop from the floor and subsequently lowering or dropping the same with a sudden push, as usually done in handling a mop with a stick for floor-polishing purposes, the valve provided in the tin firmly attached to the mop-stick, will open or be lifted from its seat for a moment due to inertia so as to allow a small portion of 107

the polishing liquid to flow out, whereupon the spring controlling the valve, will immediately act to return the valve to its seat so that liquid can never be discharged at once in excess of what the valve is adjusted to allow to flow out, whereas by repeated manipulations any desirable larger amount of liquid can be discharged. In the accompanying drawing forming a part of this specification and showing for purposes of exemplification a preferred form and manner in which the invention may be embodied and practised, but without limiting the claimed invention to such illustrative instance:

15 Figure 1 is a perspective view of a floor polishing implement and Figure 2 is a view in vertical section of a tin provided with means herein referred to in accordance with the present invention.

20 The floor polishing implement shown in Figure 1 comprises, as usually, a mop *a*, a handle or stick *b* firmly attached to the mop by means of a tubular extension or sleeve of the latter and a wing screw *c*, and a receptacle or tin *d* containing the polishing liquid and also rigidly connected to the handle *b* by means of a sleeve or clip *e* and a pair of wing screws *f* and *f'*. The implement shown and so far described may be supposed to be of known construction.

The receptacle or tin *d* is provided with a cover *g* as usually. In the bottom of the tin an aperture *h* is provided and circumferentially reinforced by means of a washer or ring *h'* soldered to the outer surface of the bottom and constituting the seat of the valve *i* of globular form. Obviously the reinforcing ring or annular plate *h'* may be dispensed with, if the bottom of the tin is of sufficient thickness or strength to afford in itself a reliable means for the provision of the valve seat. In the upper part of the inner surface of the side wall of the tin a bracket *l* is firmly attached either by soldering or in any other appropriate way, and a coiled spring *k* is provided in the tin to connect, with a moderate tension, the bracket *l* with the ball valve *i*, a hook or the like being provided in the valve for the connecting purpose. If desired or preferred a reinforcing plate may be inserted between the bracket and the wall of the tin, as shown, and the same may be firmly connected to the contiguous parts by soldering or in any other suitable manner.

55 Obviously in lieu of a single valve aperture a plurality of similar valves and apertures may be provided, as already mentioned herein.

From the foregoing it is believed, that the advantages and novel features of my invention will be readily understood and, therefore, further detail description is deemed unnecessary. It is apparent, however, that in carrying out my invention some changes from 65 the construction herein shown and described,

may be made without departure from the spirit and scope of the invention.

What I claim is:

In a floor-polishing apparatus, in combination, a handle adapted to manipulate a floor-polishing element, a closed receptacle attached to the handle for containing a liquid or floor polishing substance and the like the bottom of the receptacle being provided with an aperture forming a valve seat on the outer surface of the body, a valve body associated with the valve seat, and a coil spring connected to the valve body and arranged through the aperture and having its inner end connected to the inner surface of the receptacle near the top of the latter and acting to yieldingly connect the valve body to the receptacle.

In testimony whereof I affix my signature.

JOHANN TUREK.
